UNITED STATES PATENT OFFICE.

CHARLES H. FERGUSON, OF VALHALLA, NEW YORK, ASSIGNOR TO HOME ELECTRIC LIGHTING COMPANY, OF EAST ORANGE, NEW JERSEY, A CORPORATION OF NEW JERSEY.

INTERNAL-COMBUSTION ENGINE.

Original application filed December 27, 1919, Serial No. 347,775. Divided and this application filed October 29, 1921. Serial No. 511,409.

To all whom it may concern:

Be it known that I, CHARLES H. FERGUSON, a citizen of the United States, residing at Valhalla, in the county of Westchester and State of New York, have invented certain new and useful Improvements in Internal-Combustion Engines; and I do hereby declare the following to be a full, clear, and exact description of the invention, such as will enable others skilled in the art to which it appertains to make and use the same.

My invention consists in the novel features hereinafter described, reference being had to the accompanying drawings which represent one embodiment of the same, selected by me for purposes of illustration, and the said invention is fully disclosed in the following description and claims.

The object of my invention is to provide an internal combustion engine adapted especially to be combined with a crank shaft carrying a rotary fan for cooling the engine cylinder and supported by the supporting fan casing so as to insure the proper alignment and connection of the parts, and the efficient operation thereof, the construction being especially designed for directly operating an electric generator, the rotary armature of which is carried by the engine shaft, and constituting therewith a portable electric power plant. Such a power plant is particularly adapted for lighting of suburban homes, camps and summer cottages, garages, boats, boat houses, barns and out buildings, and other buildings or places where electric current for lighting, heating or power purposes may be desired.

This application is a division of my former application for Letters Patent of the United States filed December 27, 1919, Serial No. 347,775.

In the accompanying drawings,

Fig. 1 represents an elevation of a portable electric power unit having my present invention embodied therein.

Fig. 2 is a vertical central sectional view of the apparatus illustrated in Fig. 1.

Fig. 3 is a detail perspective view showing a portion of the engine cylinder, the main shaft, the crank and engine valve mechanism, the parts being illustrated in separated relation for greater clearness.

Fig. 4 is a detail view of a portion of the engine shaft, and the ignition timing mechanism the parts being illustrated in perspective and in separated relation for greater clearness.

Referring to the drawings, and particularly to Figs. 1 to 5 inclusive, 1 represents what I term the fly-wheel housing which is supported upon a suitable base 2 and constitutes in effect the main frame of the apparatus, and also serves as a fan casing, as hereinafter described. This fly-wheel housing is provided with parallel vertical walls, 3 and 4, and a curved peripheral wall, 5, to completely enclose the fly-wheel indicated at 6, which is provided with a plurality of fan blades, indicated at 7, the fly-wheel being carried on a main shaft 8, which serves both as the crank shaft of the engine and the armature shaft of the motor generator. In the organization of power plants in which an engine and generator are directly connected, much difficulty is usually experienced in securing the proper alignment of the crank shaft of the engine and the armature shaft of the generator. I obviate this difficulty entirely by providing accurately aligned bearings for the armature shaft, and forming the engine crank separate from the armature shaft, and connecting the engine in accurate operative relation to the crank and the bearings for the armature shaft, so that the parts may be readily assembled, and will be positively held in accurate relative positions.

To this end I provide the front wall 3 of the fly-wheel housing with an annular aperture, indicated at 9, which is accurately bored and faced to form an annular guiding and positioning portion to receive a shouldered bearing plate 10, which fits the aperture 9 and is secured to the fly-wheel housing by screws or bolts in any desired manner so as to accurately center the shaft bearing carried centrally thereof. This bearing plate 10 is provided centrally on its inner face with a bearing preferably of the ball bearing type, indicated at 11, for the shaft 8, and the said plate 10 has cast with it a downwardly extending crank case, indicated at 12, which provides an annular portion 13 to which the engine cylinder 14 is bolted, thus accurately determining the relation between the engine

cylinder and piston, and the main shaft 8. The inner face of the crank case 12, as best shown in Fig. 4, is provided with an annular recess 15 surrounding the shaft 8 and provided with a port 16 communicating with a lateral aperture 17 connected, as hereinafter described, with the carburetor for supplying the explosive mixture to the engine. Within the recess 15 is located a rotary valve 18, see Fig. 4, which normally closes the port 16, while a cut-away portion, or port 19 in the valve, is adapted to open the port 16 once in each revolution of the valve. The valve is operated by means of an eccentrically located pin or stud 20 projecting from one face of the valve, and engaging an aperture 21 in a counter-weight portion 22 of the engine crank 23, which is formed separately from the shaft 8 and provided with a sleeve 24 fitting over a reduced portion of the shaft 8 and secured thereto by means of a spline or otherwise and held from longitudinal movement on the shaft by means of a set screw 25. In order to hold the rotary disc valve 18 firmly on its seat, I conveniently provide a disc or washer 26 (see Fig. 4) formed of thin spring material and shaped similarly to the disc valve 18 and interposed between the disc valve 18 and the rear face of the crank 23, and counter-weight portion 22, said spring disc being provided with an aperture 27 to engage the stud 20 of the disc valve. 28 represents the piston mounted in the cylinder 14, and being of the usual type employed in a two cycle engine. 29 represents the piston rod which is connected to the piston at one end, and at the other end carries a ball bearing 30 surrounding the crank pin 31, which is screwed into a threaded opening in the crank 23. The outer end of the crank case is formed with an aperture to facilitate the assembly of the parts of the crank and engine valve, and this opening is closed by means of a plate 32 (see Fig. 2).

The engine cylinder 14 is provided with an inlet port 33 and exhaust port 34 which may be connected to a muffler of any desired or usual form. The inlet port 33 communicates with a passage 35 alongside of the cylinder and connecting with a port 36 in the crank case, as shown in Figs. 3 and 4, so that the charge drawn into the crank case when the disc valve opens the port 16, and compressed by the outward or power stroke of the piston, will be transferred through the port 36 and passage 35 to the inlet port 33, to constitute the next succeeding charge for the cylinder. It will be understood that the cylinder will also be provided with the usual spark plug or other ignition means, indicated at 37, and the lower end of the cylinder, which con-

stitutes the head of the cylinder, is preferably provided with radially disposed flanges, spikes, or other form of projections, indicated at 38, for the purpose of rapidly radiating heat to facilitate the cooling of the cylinder. The lower end of the cylinder is also surrounded by a casing, indicated at 39, and communicating with a discharge orifice 40 from the fan casing or fly-wheel housing 1, so that the air drawn into the casing 1 by the fan and discharged therefrom will pass out through the aperture 40 and casing 39 directly over, around and past the lower end of the cylinder, with its radiating projections, and thereby assist in cooling the engine. I also prefer to provide the crank case with an exterior metal shell 41 which is provided with air apertures 42, and the bearing plate 10 is also provided with apertures, indicated at 43, so that air may be drawn in around the crank case, thereby keeping the crank case and the crank and the adjacent bearing for the shaft 8 cool, these parts not being so highly heated as the engine cylinder, and the air is then delivered, as before stated, to the exterior of the engine cylinder, where it takes up additional quantities of heat. As hereinafter explained, I also provide for drawing the air in part into the fly-wheel housing of fan casing 1 from the portion of the apparatus enclosing the motor generator, so as to maintain it cooled also, and prevent the heating thereof.

The rear wall 4 of the fly-wheel casing is provided with an aperture, indicated at 44, the marginal portions of which are turned and planed coaxially with the aperture 9 in the wall 3, and said marginal portions are preferably provided with a guiding and positioning annular bead 45 which receives an annular casing 46 carrying the field magnets 47 of the motor generator. The annular casing 46 carries on its outer end a bracket or casting 48 which carries the centrally outer bearing 49 of the main shaft 8, and also the brushes 50 of the motor generator. It will be seen that the provision of the lateral walls of the housing with coaxial apertures and guiding and positioning portions to receive the plate 10 and the casing 46 in which are located centrally the shaft bearings, insures in the first place the accurate alignment of the crank shaft with respect to the casing, and the crank case carried by plate 10. The further provision on the crank case of plate 10, of means for supporting the cylinder in accurate position with respect to the crank case insures the correct positioning of the cylinder with respect to the crank shaft, and its bearings, so that the entire construction can be readily assembled by comparatively unskilled labor with the certainty that the parts will be correctly

positioned with respect to each other. Moreover, the crank is formed separately from the shaft, and this facilitates the assembling of the parts. It will also be seen that the 5 fly-wheel is mounted between the bearings, which tends to reduce vibration and insure steadiness in operation, and the cylinder is supported entirely by the crank case, and plate 10 on the opposite side of the adjacent shaft bearing, from the fly-wheel so that the engine cylinder is at all times held in fixed 10 relation with the crank case and the housing 5, and cannot lose its accurate relation to the crank shaft through vibration or otherwise. 15 The shaft 8 as will be clearly seen, carries the armature 51 and commutator 52, the outer end of the shaft extending through the bearing 49 and being provided beyond said bearing with a brush 53 for engaging a segment 20 54 connected with the igniter 37 of the engine, and the outer end of the shaft 8 is provided with the usual means, as projections 55, see Fig. 4, for receiving a hand crank 56, indicated in dotted lines in Fig. 2, 25 a. detachable cover or cap 57 being placed over the end of the shaft 8 when the crank is not in use. It will be seen by the construction herein shown and described that the main shaft 8, which is both the armature shaft of the motor generator and the crank shaft of the engine, is supported in exact position with respect to the engine cylinder, and the crank, so that the correct 30 operation of the respective parts for starting the engine and also for generating current is secured and maintained.

I conveniently employ an annular tank, indicated at 58, which surrounds the field magnets 47 and field magnet casing 46 and 40 which will contain the supply of gasoline or other motor fuel, and I prefer to add the lubricating oil for the engine cylinder directly to the motor fuel, and feed it therewith, although the engine may be lubricated in any other desired manner. I also provide a shell or casing, indicated at 59, surrounding the armature 52 and brushes 50, and provided with ventilating apertures 60. It will now be seen that, as before stated, 45 when the apparatus is in operation, the air will not only be drawn into the fan casing or fly-wheel housing 1 from the apertures 42 adjacent to the crank case, but a portion of air, which I prefer to limit by regulating 50 the size of the openings 60 will be drawn into the shell 59 and will pass around the commutator 52 and brushes, and between the armature and field magnets, to the fan casing 1, thereby keeping all parts of the generator cool, and as these parts do not become 55 very highly heated, this air, as well as the air drawn in around the crank case, is discharged through the aperture 40 against the engine cylinder, and is still capable of taking 60 large quantities of heat therefrom.

The motor fuel is taken from the tank 58 by means of a pipe 61 which delivers it to the carburetor 62, which may be of any usual or desired construction. From the carburetor, a pipe 63 leads to the passage 17 in the 70 crank case communicating with the valve port 16 before described for supplying explosive mixture to the cylinder.

It will be noted that this apparatus is extremely compact, and in practice it is of 75 such small size, that it may be readily carried by hand, and I have shown it provided with a handle 79 formed of sheet metal and connected by strips 80 with adjacent portions of the casing, so that it can be conveniently carried.

What I claim and desire to secure by Letters Patent is:—

1. In an internal combustion engine, the combination of a supporting base and a fly 85 wheel casing supported thereby, said casing having parallel walls provided with coaxial apertures and having on their exterior faces coaxial guiding and positioning devices, a bearing supporting means engaging each of 90 said coaxial guiding and positioning devices on the said casing and being secured to the exterior faces of said parallel walls respectively, bearings located centrally in said bearing supports, one of said bearing 95 supporting means being provided with an integral crank case formed with a face to receive an engine cylinder and hold it with its axis perpendicular to the common axis of said bearings, a cylinder secured to said face 100 and supported entirely thereby, independently of the base, a shaft engaging said bearings, a balance wheel on said shaft between the parallel walls of the casing, a 105 crank on said shaft in said crank case, a piston in said cylinder and a piston rod connecting said piston and crank.

2. In an internal combustion engine the combination of a main casing having parallel vertical walls provided with co-axial circular apertures and coaxial annular guiding and positioning portions adjacent thereto, a circular plate engaging the guiding and positioning portions adjacent to one of said 110 apertures, and provided with a centrally located bearing, a crank case and a supporting portion to receive an engine cylinder with its axis perpendicular to the axis of said bearing, a casing engaging the guiding and positioning portions adjacent to the 115 other aperture in the main casing and provided with a centrally located bearing, a shaft mounted in said bearings, a crank on said shaft within the crank case, a cylinder secured to and supported by said supporting portion of the crank case, a balance wheel carried by said shaft between said 120 bearings, a piston in the cylinder, and a piston rod connecting said piston and crank.

3. In an internal combustion engine the 125

- combination of a main casing having parallel vertical walls provided with coaxial circular apertures and coaxial annular guiding and positioning portions adjacent thereto, a circular plate engaging the guiding and positioning portions adjacent to one of said apertures and provided with a centrally located bearing, a crank case adjacent thereto and having an aperture on its outer side, and a portion to receive and support an engine cylinder with its axis perpendicular to the axis of said bearing, a part circular in cross section engaging the guiding and positioning portions adjacent to the other aperture of the main casing and provided with a centrally located bearing, a shaft engaging said bearings, a detachable crank in said crank case secured to said shaft, a cylinder secured to and supported entirely by said supporting portion of the crank case, a piston in said cylinder, a piston rod connecting said piston and crank, a detachable closing plate for the aperture in the crank case, and a balance wheel on the shaft located between said bearings and adjacent to the crank case.
4. In an internal combustion engine, the combination with a supporting fan casing having a supporting base and parallel walls, provided with coaxial circular apertures, a circular plate fitting one of said apertures and provided with a shaft aperture, and a shaft bearing located therein, said plate having formed integrally therewith a crank case, and a support for an engine cylinder, a casing engaging the other wall of the fan casing, and a coaxial shaft bearing carried thereby, a shaft supported in said bearings, a rotary fan in the fan casing and secured to said shaft between said bearings, a detachable crank in said crank case, secured to said shaft, a cylinder and a piston rod connecting said piston and said crank, said fan casing being provided with a single discharge aperture adjacent to and directed toward the head of the cylinder, and said plate being provided with air inlet apertures adjacent to the crank case, an exterior casing surrounding the crank case, and provided with air inlet apertures communicating with the apertures in said plate, whereby the air will be drawn in to the fan around the crank case to cool it, and will be discharged upon the cylinder head to effect a further cooling action.
5. In an internal combustion engine, the combination with a supporting fan casing having a supporting base and parallel walls, provided with coaxial circular apertures, a circular plate fitting one of said apertures and provided with a shaft aperture, and a shaft bearing located therein, said plate having formed integrally therewith a crank case, and a support for an engine cylinder, a casing engaging the other wall of the fan casing, and a coaxial shaft bearing carried thereby, a shaft supported in said bearings, a rotary fan in the fan casing and secured to said shaft between said bearings, a detachable crank in said crank case, secured to said shaft, a cylinder and a piston rod connecting said piston and said crank, said fan casing being provided with a single discharge aperture adjacent to and directed toward the head of the cylinder, and said plate being provided with air inlet apertures adjacent to the crank case for drawing in air around the crank case to cool it, the air being discharged upon the cylinder head to effect a further cooling action.
5. In an internal combustion engine, the combination with a supporting fan casing having a supporting base and parallel walls, provided with coaxial circular apertures, a circular plate fitting one of said apertures and provided with a shaft aperture, and a shaft bearing located therein, said plate having formed integrally therewith a crank case, and a support for an engine cylinder, a casing engaging the other wall of the fan casing, and a coaxial shaft bearing carried thereby, a shaft supported in said bearings, a rotary fan in the fan casing and secured to said shaft between said bearings, a detachable crank in said crank case, secured to said shaft, a cylinder engaging said cylinder support, a piston in said cylinder and a piston rod connecting said piston and said crank, said fan casing being provided with a single discharge aperture adjacent to and directed toward the head of the cylinder, and said plate being provided with air inlet apertures adjacent to the crank case, an exterior casing surrounding the crank case, and provided with air inlet apertures communicating with the apertures in said plate, whereby the air will be drawn in to the fan around the crank case to cool it, and will be discharged upon the cylinder head to effect a further cooling action.
6. In an internal combustion engine, the combination of the crank shaft, supporting bearings therefor, and a crank case adjacent to one of said bearings, a cylinder secured to the crank case, a piston in said cylinder, a piston rod connecting said piston and crank, an annular valve seat in the crank case surrounding the shaft, an annular valve engaging said seat, said valve and the crank having the one a projection to engage an aperture in the other to effect the joint rotation of the valve and the crank, and an annular spring washer interposed between the valve and the crank and provided with an aperture engaging said projection to effect the joint rotation of said spring washer with the crank and valve.
7. In an internal combustion engine the combination with a supporting casing, provided with coaxial shaft bearings, and a crank case adjacent to one of said bearings, a cylinder secured to said crank case, a shaft engaging said bearings, a detachable crank in the crank case having a sleeve engaging said shaft, a piston in the cylinder, a piston rod connecting the piston and crank, said crank case being provided with an annular valve seat surrounding said sleeve, an annular valve surrounding said sleeve and engaging said seat, said crank and valve having the one, a projection engaging an aperture in the other, and an annular spring washer surrounding said sleeve and located between the valve and the crank, and provided with an aperture engaging said projection.
- In testimony whereof I affix my signature.
CHARLES H. FERGUSON.
